CLAIM

I claim the ornamental design for a pet utensil handle, as shown.

DESCRIPTION

FIG. 1 is a front view of the pet utensil handle;

FIG. 2 is a right side view of the pet utensil handle;

FIG. 3 is a bottom view of the pet utensil handle;

FIG. 4 is a back view of the pet utensil handle;

FIG. 5 is a left side view of the pet utensil handle;

FIG. 6 is a top view of the pet utensil handle; and,

FIG. 7 is a perspective view of the pet utensil handle.

The portions shown in broken line are for illustrative purposes only and form no part of the claimed design.
